SPRING-POWERED KEY ACTION

James P. Wesley, Glendale, Calif.

Application August 28, 1946, Serial No. 693,483

3 Claims. (Cl. 197—17)

1

This invention relates to key actions for typewriting and other key-operated machines.

In the key actions of typewriting machines, it is conventional practice to so connect the key lever with the type bar that the latter, after being moved to printing position, may return to normal position independently of the key lever, to permit operation of another key lever without waiting for the previously operated key lever to return to normal position. This has been accomplished by providing a releasable connection between the key lever and the type bar, and means to release said releasable connection between the key lever and the type bar after the latter has been given sufficient momentum to effect the printing and just before movement of the key lever has been completed. In prior actions, however, the type bar is moved toward printing position by the key lever and the momentum of the type bar and the force with which the printing character thereof strikes the printing ribbon depends upon the force of the impact of the finger with the key lever. As a result of this, operation of the typewriter causes considerable fatigue on the part of the operator and the printed characters vary as to tone.

The primary object of the present invention, therefore, is to provide an improved typewriter action by means of which the above objections of prior actions are overcome.

In carrying out the present invention in connection with a typewriter, I provide a power unit for moving the type bar to printing position, means whereby the potential energy of said unit is increased as the key lever is depressed, and means to automatically disconnect the key lever and type bar when the potential energy of the power unit is raised to a predetermined degree and before depression of the key lever has been completed. When the power unit actuates the type bar, the increased energy thereof is spent, so that relatively weak springs may return the key lever and type bar to their normal positions and reset the detachable connection between the same for the next operation of the action. Thus, the operation of the present action does not depend upon the force of impact of the finger with the key lever. Instead, the operation depends only upon the distance of movement of the key lever, and the momentum of the type bar in moving to printing position is always the same and is caused by the power unit instead of by variable manual force applied by the operator to the key lever. Consequently, operation of the present action causes less fatigue of the operator, and the

2

characters are always printed in the same tone so that the printed page is clear and easy to read and has a uniform and slight appearance. Also, care on the part of the operator is unnecessary, and greater typewriting speed is made possible.

A further object of the invention is to provide a key action for key operated machines, which is highly efficient in operation, comparatively simple in construction, and otherwise well adapted to meet the requirements for successful commercial use.

The exact nature of the present invention, as well as other objects and features thereof, will become apparent from the following description when considered in connection with the accompanying drawing, in which:

Figure 1 is a cross sectional view of a typewriting machine having one form of key action embodying the present invention;

20 Figure 2 is a fragmentary plan view showing the parts of a single key action of the form embodied in the machine of Figure 1;

Figure 3 is a perspective view of the construction shown in Figure 2;

25 Figure 4 is an enlarged fragmentary vertical section through the parts of the action, taken on line 4—4 of Figure 1;

Figure 5 is a view similar to Figure 4, showing the key lever depressed;

30 Figure 6 is a fragmentary transverse section taken on line 6—6 of Figure 1.

Referring in detail to the drawing, wherein one embodiment of the invention is merely illustrated by way of example, 5 indicates the frame of a typewriting machine, and 6 the platen thereof. A wide bar or plate 7 extends across the machine and carries the pivots 8 for the type bars, one of which is shown at 9. A key lever 10 is pivoted upon the pivot pin 8 of each type bar 9, and each key lever is returned to its normal elevated position by spring 11. Also, each type bar 9 is swung away from the platen 6 to a normal inoperative position by means of a spring 12.

In accordance with the illustrated embodiment 45 of the invention, each key lever is provided between its ends with a laterally projecting cam lug 13 beneath which is normally engaged a latch element 14 carried by a laterally flexible leaf spring 15 which is attached to a forwardly projecting short arm 16 provided on the pivoted end of the associated type bar 9. Also, the arm 16 is provided at its free forward end with a lateral lug 17 which bears upon a leaf spring 18 forming part of a power unit mounted upon the bar or plate 7. 55 This power unit also includes a block 19 fixed

upon the bar or plate 7 and having one end of the spring 18 fixed thereon. Fixed upon the bar or plate 7 beneath the latch element 14 is a cam plate 20, and the arrangement is such that the latch element 14 is normally engaged beneath the cam 13 of key lever 10 for being depressed by the latter. Thus, as the key lever 10 is depressed, the type bar 9 is swung slightly further away from the platen 6 and arm 16 is caused to lower for increasing the potential energy of the power unit 18, 19. As the key lever 10 moves downwardly, the cam 20 causes lateral movement of latch element 14 as allowed by spring 15, until said latch element 14 is ultimately disengaged from beneath the cam 13 as illustrated in Figure 5. This occurs slightly before depression of the key 10 is completed, and it results in freeing the type bar 9 from the associated key lever 10 so that the energy of the unit 18, 19 is released so that said unit instantaneously swings the type bar 9 upwardly and rearwardly into printing position as shown by dotted lines in Figure 1. When this occurs, the increased energy of the power unit is spent so that upon removal of the finger from the actuated key lever 10, the springs 11 and 12 will return the key lever 10 and type bar 9 to their normal positions as shown in Figure 1. When the parts 9 and 10 thus return to their normal positions under the influence of the springs 11 and 12, the latch element 14 passes downwardly along the inclined edge of cam 13 until said latch element is located completely below said cam 13, whereupon the spring 15 moves the latch element 14 laterally toward the key lever 10 and engages it beneath the cam 13. In this way, the latch element 14 is reset in latching position so that the action is conditioned for the next operation thereof.

It will of course be understood that the strength of spring 12 is sufficient to overcome the action of spring 18 and the resistance offered by spring 15 in causing passage of the latch element 14 past and below the cam 13, in the resetting operation. On the other hand, when the key lever 10 is depressed, the energy of spring 18 is increased to a point above the strength of spring 12 so that such increased energy of spring 18 will be sufficient to move the type bar 9 to printing position against the action of spring 12.

From the foregoing description, it is believed that the construction, operation and advantages of the present invention will be readily understood and appreciated by those skilled in the art. While I have illustrated, merely by way of example, one specific embodiment of the present invention, it will be understood that many widely different modifications of the invention are possible. Accordingly, the invention broadly contemplates any mechanism in which energy supplied by the finger in depressing the key is used to raise the potential energy of some power unit; in which a releasing mechanism then frees the potential energy of this unit, and the energy thus released then drives the actuated part or type bar so as to cause the latter to be actuated or moved to printing position; and in which some device is used so that the key and actuated part

or type bar are returned to their original positions and the mechanism is reset when the finger is removed from the key. The important facts are that the mechanism is such that the operation of the action does not depend upon the force of impact of the finger with the key lever, but depends only upon the distance of movement of the key lever. Also, the momentum of the type bar in moving to printing position is always the same and is caused by the power unit instead of the variable manual force applied by an operator to a key lever. It will accordingly be apparent that the present action will cause less fatigue of the operator, and that the characters will always be printed in the same tone without any exercise of care on the part of the operator and so that greater typewriting speed is made possible.

Having now fully described my invention, what I claim as new is:

- 20 1. In a typewriting machine, the combination of a key lever having a lateral keeper cam, a type bar having an arm provided with a lateral lug, a spring attached to said arm and carrying a latch engageable beneath the keeper cam to connect the key lever and type bar, a power unit including a spring depressable by the lug of said arm upon depression of the key lever to have the potential energy thereof increased, and a cam arranged in the path of said latch to disengage it from beneath the keeper cam and thereby disconnect the type bar and key lever before movement of the key lever is completed, whereby the increased energy of the power unit spring is utilized to swing the type bar to printing position.
- 25 2. The construction defined in claim 1, in combination with springs for returning the key lever and type bar to their normal positions and to reset the latch beneath the keeper cam when the increased energy of the power unit spring is spent and the finger is removed from the key lever.
- 30 3. In a typewriting machine, the combination of a key lever having a lateral keeper cam, a type bar having an arm, a spring attached to said arm and carrying a latch engageable beneath the keeper cam to connect the key lever and type bar, a power unit including a spring coacting with said type bar so as to have its potential energy increased upon depression of the key lever, and a cam arranged in the path of said latch to laterally move and disengage it from beneath the keeper cam and thereby disconnect the type bar and key lever before movement of the key lever is completed, whereby the increased energy of the power unit spring is utilized to swing the type bar to printing position.
